UNITED STATES PATENT OFFICE

2,660,868

STOCKING

Kurt F. Naumann, Stony Creek Mills, Pa., assignor to Rosedale Knitting Company, Reading, Pa., a corporation of Pennsylvania

Application July 28, 1950, Serial No. 176,313

1 Claim. (Cl. 66—179)

1

This invention relates to stockings. More specifically, it is concerned with a stocking produced from synthetic yarn or yarns, such as nylon, which are non-absorbent and therefore do not have the capacity to dissipate the moisture as the foot of the wearer perspires in the shoe, particularly in the region of the large toe joint or ball of the foot.

My invention is directed toward overcoming the above mentioned drawback. How this objective is realized in practice will appear from the following detailed description of the attached drawings, wherein:

Fig. 1 is a view in side elevation of a full-fashioned lady's stocking conveniently embodying my invention;

Fig. 2 shows the fore part of the foot of the flat-knitted blank from which the stocking is formed; and

Fig. 3 is a fragmentary diagrammatic view showing the yarn interloopment in the ball region of the blank within the area of the broken line rectangle III in Fig. 2.

The illustrated stocking is generally of well known construction, and it is to be understood, is knitted throughout from nylon or like synthetic yarn or yarns, except as hereinafter pointed out, with a boot portion 5 that tapers downwardly to the ankle 6, and with a foot 7 of which latter the heel 8, the portion 9 of the sole and the toe 10 are reinforced, the reinforcement terminating in lines 12 and 13 contoured to produce what is ordinarily known as a "cradle" effect.

To knit the portions in the foot between the courses A—A and B—B in Figs. 1 and 2 in the region of the ball of the foot, in accordance with my invention I employ for the top or instep area 14, a nylon yarn which may be the main body yarn used in the other parts of the stocking, and for the formation of the sole areas of the blank at 40 said region, I employ absorbent yarns of cotton or the like preferably of a higher count than said nylon yarn. In the knitting, the nylon yarn is fed from one carrier, and the cotton yarns individually from separate carriers. The traverse 45 of the carriers is so controlled that selvage loops of the nylon yarn are interlocked, as shown in

2

Fig. 3, with selvage loops of the cotton yarns along inwardly curved sutures 15, with consequent formation of gussets or panels 16 of liberal area at the ball region of the stocking foot. The toe portion 18 of the foot, beyond the course B—B, may be formed in a way commonly practiced in the art and therefore requires no description. When the selvage edges of the blank are united by the usual back seam, the areas 16 will be merged into one to form a section of the cradle sole reinforcement. By reason of being of cotton, the areas 16 at the ball of the stocking foot will effectively absorb perspiration and carry it up to the level of the shoe top where it may freely evaporate when the stocking is worn.

As will be readily understood by skilled knitters, the substitution of cotton yarn carriers for the usual reinforcing nylon carriers to form the patches 16 can be effected without any substantial delay in the knitting cycle, so that the stockings of my invention can be produced substantially as economically as ordinary stockings in which the foot is reinforced throughout the sole with nylon yarns.

Having thus described my invention, I claim:

As a new article of manufacture, a full-fashioned stocking with a closure seam extending longitudinally of the back of the leg and foot bottom, produced mainly from non-absorbent yarn, and having, at opposite sides of the seam in the region of the ball portion of the foot, complementary panel areas of absorbent yarn which extend partway into the instep from the seam and which are knitted into selvage loops of the instep.

KURT F. NAUMANN.
